(57) **CLAIM**

The ornamental design for sand jewelry, as shown and described.

DESCRIPTION

FIG. 1 is a front perspective view of sand jewelry showing my new design;

FIG. 2 is a front elevation view of the sand jewelry;

FIG. 3 is a rear elevation view of the sand jewelry;

FIG. 4 is a bottom view of the sand jewelry;

FIG. 5 is a top view of the sand jewelry; and,

FIG. 6 is a side view of the sand jewelry.

The portion of the drawings in broken lines forms no part of the claimed design.
